UNITED STATES PATENT OFFICE.

PHILIP HAAS, OF DAYTON, OHIO.

FLUSHING-VALVE MECHANISM.

Application filed June 2, 1925. Serial No. 34,307.

My invention consists in the novel features hereinafter described, reference being had to the accompanying drawings, which illustrate one embodiment of the same, selected by me for purposes of illustration, and the said invention is fully disclosed in the following description and claims.

The object of my invention is to provide a flushing valve mechanism for water closets of the utmost simplicity, which can be manufactured cheaply and readily installed, and which can be readily removed for examination, adjustment, repair or replacement of parts by anyone, as an ordinary householder, and which is absolutely efficient and reliable in operation. One of the objects of my invention is to dispense with the ordinary metallic overflow pipe which is liable to become perforated by corrosion below the water line, and produce leakage of water and to substitute therefor an overflow pipe formed of a light material which is not affected by water and not subject to corrosion, preferably such material as hard rubber, celluloid, or the like, which is interposed in the connections between the flushing valve and its operating mechanism and extends through the flushing valve and forms a guiding stem for the same. In the ordinary flushing tank, the usual metallic overflow pipe requires a fitting projecting above the bottom of the tank, and necessitates the arrangement of the valve seat for the flushing valve at a distance above the bottom of the tank, so that it is impossible to completely drain the tank, and it is therefore impossible to prevent the collection of sediment which it is very difficult to remove without disconnecting the tank, and which in some instances produces unsanitary conditions. According to my present invention, by dispensing with the ordinary overflow pipe and employing the form of overflow pipe above mentioned, I am enabled to locate the flushing valve seat flush with, or even slightly below, the bottom of the tank. Therefore, the water adjacent to the bottom of the tank may flow out at each flushing action and the tank may be completely drained when desired, so that the collection of sediment is prevented, and in case any sediment should collect, it may be very readily removed and the tank thoroughly cleaned, without disconnecting it from its connections. By so arranging the overflow

pipe in the manner described, an additional capacity is added to the tanks as now made, and this permits also the formation of tanks of the same capacity as the present tanks and of approximately one inch less depth 60 on the side wall, which effects a very considerable economy in the manufacture of these tanks, especially in solid ceramic ware, and such tanks will also take up a correspondingly less amount of room in a bathroom or toilet. I also employ a flushing valve of unique character in this instance, mounted upon the centrally located overflow pipe before mentioned, and preferably in the form of a hollow body of flexible material, as rubber, having a flexible and elastic seat engaging portion formed by the lower portions of the hollow walls to engage the flushing valve seat, and adapted to contain 70 a certain amount of water, which acts as a weight for the valve and which may be varied to secure the proper or desired operation of the valve. The said flushing valve is suspended freely in the tank, preferably without the use of guides and connected with 75 a flexible operating device, as a cord, wire or chain, which in the preferred form of my invention, engages guiding supports in the lid of the tank, and includes a unitary depending portion, which is connected with 80 the overflow pipe and an exterior depending portion provided with an operating handle, the valve and its operating connection being so counter-balanced, that the valve will remain in any position where it may be moved while supported in part by the water in the tank, in which it is immersed, but as soon as the support or buoyancy of the water is removed from the valve, as the flush tank 85 is emptied, the weight of the valve and the unitary depending portion of its operative connection, will be greater than that of the exterior depending portion of the operative connection, so that the valve will automatically return to its seat, as soon as the water has run out of the tank far enough to expose the valve and relieve it of the support or buoyancy of the water.

My invention also contemplates the construction of the flushing valve in such manner that the seat engaging portion thereof does not accurately fit the flushing valve seat on coming in contact therewith, thus permitting a slight and restricted leakage of water past the said valve, for the purpose

of effecting the after-fill of the closet bowl and its seal, such flow or leakage continuing until water has accumulated in the tank to a sufficient height so that a downward pressure of the water upon the flexible wall of the valve will slightly expand the same into perfect contact with the seat and produce a tight joint therewith. In some instances, instead of distorting the shape of the valve, I may distort the shape of the valve seat, but in either case the operation will be the same. This greatly simplifies the construction of the apparatus and does away with the auxiliary pipe usually employed in flushing tanks to effect what is known as the after-fill.

While it is not essential that the operating connection for the flushing valve, which is wholly or in part formed of flexible material, as chain, etc., should be supported by the tank cover, this is my preferred construction, as it obviates the necessity of providing supports for the valve operating mechanism in the tank, and simplifies the construction, and further, by the removal of the lid of the tank, the entire flushing valve, overflow pipe, and the operative connections for the flushing valve, may be instantly removed for inspection or repair. I also prefer to so locate the supports for the operative connections for the flushing valve on the lid of the tank, that the tank lid may be raised into an approximately vertical position and moved toward the center of the tank, and held in that position while the flushing valve is operated to permit the observation of the valve under working conditions, and see that it and its operative connections are properly installed.

Referring to the accompanying drawings, Fig. 1 represents a sectional view of a flushing tank embodying my invention, and connected with a closet bowl, the bowl being partly broken away.

Fig. 2 is an enlarged view of the flushing valve and overflow pipe, partly broken away.

Fig. 3 is a sectional view on the line 3—3 of Fig. 1, to the overflow pipe, and illustrating the distortion of the flushing valve with respect to the valve seat.

Fig. 4 is an enlarged sectional view showing the valve seat, flushing valve and overflow pipe located centrally thereof.

Fig. 5 is a similar view showing a modified form of valve seat, formed of rubber or other flexible material.

Fig. 6 is a plan view of a metallic valve seat which I may employ, the same being distorted out of a true circle for the purpose of receiving a valve having a truly circular seat engaging portion to provide for the after-fill.

Fig. 7 is a view representing a flushing tank embodying my invention having the

top raised and disposed centrally of the tank to permit the operation of the valve mechanism to be observed.

Fig. 8 shows the tank lid entirely removed with the valve, overflow pipe and valve operating device to permit of inspection or repair, or replacement of parts.

Referring to the drawings, 1, represents the closet bowl, provided with the flushing pipe, 2, connected with the tank, indicated at 3, which may be of any suitable material, but which is preferably made, according to modern methods, of porcelain and provided with a fitting, indicated at 4, for securing it to the flushing pipe. It will be noted by reference particularly to Figs. 1 and 4, that this fitting, 4, is provided with a flange, 4^a, engaging a counterbore, or recess, 3^a, surrounding the aperture, in the bottom, 3^b, of the tank, so that the upper face of the fitting, 4^a, is flush with the bottom of the tank, and it may be, if desired, even slightly below the upper face of the tank bottom, 3^b, so as to enable the water adjacent to the bottom to immediately flow out when the flushing valve is open, draining out all sediment, ordinarily preventing the accumulation of sediment in the tank, and enabling the tank to be thoroughly cleaned in case any sediment should collect, as where the tank has been allowed to stand for a long period without being used. The fitting, 4, is also provided with a valve seat, indicated at 6, for the flushing valve, which preferably lies below the level of the upper face of the tank. 7 represents the water inlet pipe, which is connected with a suitable fitting, indicated at 8, with a vertical pipe, 9, provided at its upper end with a float inlet valve, 10, controlling the discharge of water into the tank, through a downwardly extending pipe, 11, under the control of a float, indicated at 31, and a float lever, indicated at 23, in any usual or well known manner. As the inlet valve mechanism forms no part of my present invention, it will not be further or more particularly described, except to say that when the float is raised, as shown in Fig. 1, the inlet valve is closed, and when the float descends, the inlet valve is opened, the normal water level being indicated in dotted lines in Fig. 1. My improved flushing valve is indicated as a whole at 33, and in its preferred form comprises a hollow body formed of flexible rubber, open at the upper end and tapering at its lower end to provide the conical seat engaging portion, 33^a. The valve is provided with a central aperture therethrough surrounded by an interior sleeve, indicated at 35, the outer flexible wall of the valve being indicated at 34, and in order to give sufficient strength to the outer wall without too greatly affecting its resiliency, I prefer to provide a plurality of 123

radial webs, indicated at 36, connecting the sleeve, 35, with the outer wall, 34. The outer wall, 34, preferably extends somewhat above the sleeve, 35, although this is not essential, and the upper portion of said wall is preferably provided at its inner face with a plurality of annular beads, indicated at 38, which form guides in case it is desirable to decrease the holding capacity of the valve 10 in securing the desired balance of the valve and its operating connection.

5 represents the overflow pipe, which is preferably formed of a very light material, not affected by water, and not liable to rust or corrosion. I preferably employ for this purpose, celluloid, but other materials, such as hard rubber, bakelite, or the like may be used, or any other material which is suitable for the purpose. The overflow pipe 20 extends down through the valve and fits within the sleeve, 35, as shown in the drawing, and extends below the same a distance far enough so that when the valve is raised to its highest position, the depending portion, 5^a, of the overflow pipe will not be removed from within the valve seat so that this portion of the overflow pipe below the valve serves to prevent the valve from getting out of operative relation with its seat. 25 The lower end of the tube or pipe, 5, is preferably curved inwardly, as shown at 5^a, so as to prevent it from catching at any projecting portions of the fitting in the vertical movements of the valve. When the valve 30 is connected with the overflow pipe, it will ordinarily be held frictionally thereon, but it may be screwed thereto if desired, and in any case, I prefer to so construct the valve that when it is connected with the overflow 35 pipe in the manner shown in Figs. 1, 2 and 3, for example, portions of the lateral wall, 34, will be deflected out of a true circle adjacent to the seat engaging portion, 33^a, thereof, as clearly indicated at X in Fig. 3, so that when the valve first seats, it will permit a leak of water between it and the seat at one or more places (3 places as shown in Fig. 3), to accomplish the after-fill of the bowl, while the water is accumulating in the tank, and as soon as the water reaches a sufficient height for the additional pressure exerted from within the valve to expand the flexible side walls, 34, they will 45 so expand and make a tight joint, to stop any further leakage and remain in this position until the next flushing action. In some instances, instead of making the valve with distorted walls, I may make the seat engaging portion of the valve truly circular in 50 cross section, and provide the fitting with a distorted valve seat, as in Fig. 6, in which the fitting, indicated at 104, is provided with a distorted valve seat, 106, for the same purpose, but I prefer the construction illustrated in Fig. 3.

The upper portion of the overflow pipe, 5, is provided with overflow apertures, 5^b, preferably located slightly above the normal water level in the tank, and I also prefer to provide the upper end of the overflow pipe 70 with means for connecting it with the valve operating flexible connections. As the flexible connections I prefer to employ a ball chain, and this may be readily connected to the overflow pipe by providing a vertical slot, indicated at 5^c above one of the water apertures, 5^b, of a width sufficient to receive one of the link bars, 45^a, of the flexible chain or connection, 45. This chain or flexible connection, 45, extends from the upper end 80 of the overflow pipe through a porcelain guide formed by providing a glazed and flared aperture, 46, in a web, 44, provided on the underside of the tank lid, 50, the said lid having a depending edge portion which 85 is provided with a similarly glazed and flared aperture, 47, from which the chain depends, as indicated, and is provided with a suitable handle, 49. The flexible connection, which may be of flexible material, 90 either in whole or in part, as preferred, so long as the portions engaging the aperture, 46 and 47, are of flexible material adapted to pass easily over the glazed surface of the support, thus provides an internal depending portion, 45^b, and an external depending portion, 45^c.

It will be understood that when the device is in operation, the valve will be filled with water and the valve and the portion of the overflow pipe will be immersed in water. The valve and overflow pipe, and the flexible connection, 45, are so constructed and arranged that when the valve and overflow pipe are submerged and a part of their weight is buoyed up by the surrounding water in the tank, said parts and the interior depending portion, 45^b, will substantially balance the exterior depending portion, 45^c, so that the valve will remain in any position 100 to which it is moved while the weight of the valve and the overflow pipe, when deprived of the support of the surrounding water will readily cause the valve to move downward and seat the valve. In order to prevent the valve from being raised higher than desired, I prefer to provide the interior portion, 45^b, of the flexible connection, or the upper end of the overflow pipe with a stop washer, indicated at 51, adapted to engage 105 a shoulder, or stop, on the lid of the tank adjacent to the cross web, 44, and in order to provide a firm and easy bearing to engage the washer on opposite sides of the internal portion, 45^b, of the chain, I prefer to provide 110 the web, 44, with a lateral projection, 44^a, shown in Figs. 7 and 8, indicated in dotted lines in Fig. 1.

The parts being constructed and arranged 115 in the manner shown in Fig. 1, for example,

and the tank being filled with water to the level indicated by the dotted line, the flushing valve will be held firmly seated by the pressure of the water exerted upon the inside of the flexible wall, 34, as before stated. To effect the flushing action, the handle, 49, is pulled downwardly, thereby raising the valve and overflow pipe until the stop, 51, engages the parts, 44 and 44^a, on the lid. The valve and a considerable portion of the overflow pipe remain submerged in the water, which supports a considerable portion of their weight, and in such position their weight will be practically counterbalanced by the exterior portion, 45^c, of the flexible connection, so that the valve will remain in raised position, the water flowing out through the pipe, 2, to the closet bowl, and effecting the flushing action. When the water has been discharged so as to bring the water level below the valve, the valve and the overflow pipe, 5, are deprived of the buoyancy or support of the water and their entire weight, together with the weight of the amount of water contained within the valve, 33, will be applied to the interior depending portion, 45^b, of the chain or flexible connection, and will be sufficient to overcome the weight of the exterior depending portion, 45^c. The valve will, therefore, descend upon its seat and close the flushing outlet, but as the valve and seat do not perfectly coincide, there will be a slight leakage of water between the valve and seat, for example, as indicated at the points marked X, in Fig. 3, which will continue long enough to effect what is termed the "after-fill" of the bowl and its seal, the water level rising in the meantime within the tank. When the water level arrives at such a height that the additional pressure of the water above the valve distends the elastic sides, 34, of the valve, and causes them to fit perfectly upon the seat, this after-fill flow will cease, and no further water will be discharged until the next operation of the valve. If the valve descends too quickly when exposed and relieved of the buoyant effect of the water, it can be made to descend more slowly by decreasing the amount of water which remains in the valve. This can readily be accomplished by cutting off the marginal portion of the wall, 34, following one of the ribs, 38, which forms a guide in so cutting down the wall. If it should become necessary to add weight to the valve in order to secure its proper descent after the water has receded from it, this may be accomplished by placing one or more washers on top of the valve surrounding the overflow pipe, 5. In Fig. 2, for example, I have shown one such washer at 15. I wish it to be understood, also, that I may, in some instances increase the weight of the exterior depending portion of the flexible connec-

tion. A convenient means for doing this is to make the handle, 49, hollow, and insert small pellets of lead, or rather suitable material, indicated at 16, in Fig. 7, for example. This or other convenient means may be employed for securing the proper relative weights, which are easily secured. The frictional resistance of the ball chain over the glazed walls of the supporting apertures in the lid is very slight, and such friction as is encountered by the chain, merely causes the ball to descend quietly and easily upon its seat.

It will be seen that the tank is provided with an efficient overflow pipe in the pipe, 5, extending through the center of the valve, while the stationary overflow pipe usually employed in flush tanks is entirely dispensed with. The old form of overflow pipe was subject to many objections. In addition to being liable to be eaten through by corrosion so as to produce a leak and waste the water, it was also liable to be struck and broken off in installing or repairing parts of the tank. In my improved construction, if the overflow pipe is struck it merely moves laterally and shifts the valve slightly on its seat without offering any material resistance or being subjected to injurious strain. As before stated, I prefer to make the overflow pipe, 5, of celluloid, which is extremely strong and durable and not affected by water, and also inexpensive. It can be readily molded in the form desired. My novel construction, therefore, eliminates metal parts, i. e., the overflow pipe and its supporting action which were liable to corrosion and breakage. It will also be noted that the overflow pipe, 5, extends above the water level so that all parts of the flexible connection or chain are above the water and not subject to corrosion or rust. An additional advantage of my improved construction is that should the water level rise above the normal desired water level in the tank and high enough to reach the apertures, 5^b, in the overflow pipe, the water will be conducted straight down through the center of the valve to and through the discharge pipe, 2, and there will be no opportunity to clog as in the old construction, in which the passages from the vertical portion of the overflow pipe through the fitting at the bottom of the tank were of tortuous character and more or less easily clogged and impeded. In adjusting the valve mechanism, it will be noted that by standing the lid on edge, as indicated in Fig. 7, on the top of the tank, and moving it forward to the center of the tank, the valve may be operated in order to determine its adjustment and efficiency as the flexible connection will be held in an operative condition with the tank lid in this position. As before stated, should it be desired to remove the valve or

inspect it, or make repairs or replacements, the entire valve with the overflow pipe and valve actuating connection can be lifted off bodily with the lid and in the same manner

5 these parts can be readily removed to give access to the tank for cleaning the same should it become necessary, or for the repair of the inlet valve, or other tank connections.

In some instances I may employ a yielding valve seat of rubber or other suitable material fitted in the flushing orifice in the bottom of the tank and adapted to engage the valve, and in such case the said seat or the valve, or both, may be formed out of 10 true so as to normally contact only at separated points and leave spaces through which water may leak and perform the function of the after-fill during the first portion of the refilling of the tank. In such case the 15 valve may be made of rigid or semi-rigid material, as molded rubber, or even hard rubber or metal, if preferred, and secured to the centrally located overflow pipe by cementing or other preferred manner.

20 Thus, in Fig. 5, I have shown such a construction in which, 233, represents the valve of rigid or semi-rigid material, provided with the centrally located overflow pipe, 205, the valve having seat engaging portions for 25 engaging a flexible valve seat, 206^a, formed in a collar, 206, of rubber having an annular portion, 206^b, extending into the interior of the metal fitting, 204, to which the discharge or flushing pipe is connected in 30 the usual manner, the said collar having a shoulder, 206^c, to engage the upper surface of the fitting, 204, and said fitting is preferably provided on its interior with lugs, 204^b, for engaging the lower edge of the 35 portion, 206^b, and further supporting the collar and valve seat. As before stated, either the valve or the collar, or both, may 40 be distorted so as to provide for the after-fill, as previously described, until the tank becomes filled to a certain point when the 45 pressure of water exerted downwardly on the valve will cause the flexible valve seat to yield and tightly engage the valve.

In some instances I find it convenient also 50 to provide means for loosely guiding the flushing valve in its vertical movements within the tank, and in Fig. 7, for example, I have shown the fitting, 4, provided with four vertically extending guide pins, or 55 rods, 25, secured at intervals around said fitting, and arranged so as to guide the valve in its movements. In such case it will not be necessary to extend the pipe, 5, below the 60 bottom of the valve, and the lower portion, 5^a, may therefore be dispensed with, if desired.

It will be noted that, as shown in Fig. 7, the portions of the fitting surrounding the valve seat, between the guiding rods, 25, are 65 flush with the bottom of the tank, and the

tank will therefore drain from the bottom and prevent the collection of sediment, as before described.

What I claim and desire to secure by Letters Patent is:—

1. The combination with a flushing tank 70 provided with a flushing outlet and flushing valve seat, of a valve for engaging said seat, said seat and said valve being the one formed of yielding material and the other 75 of substantially rigid material, and being so formed as to leave space between the valve and seat when engaged without pressure, and to be forced into water tight engagement by the pressure of the water in the tank above 80 said valve, whereby when said valve is closed after a flushing operation, the said space will provide for the after-fill of the closet bowl and the valve will subsequently seat accurately when the tank is filled and operative 85 connections for said valve.

2. The combination with a flushing tank 90 provided with a flushing outlet and valve seat, of a valve having yielding seat 95 engaging portions, said valve and seat being so constructed as to leave space between them when engaged without pressure, to provide for the after-fill of the bowl, and to be brought into accurate water tight engagement by the pressure of the water in the tank, and operative connections for said valve.

3. The combination with a flushing tank 100 provided with a flushing aperture and valve seat, of a flushing valve having seat engaging portions of soft rubber, said seat and valve being constructed so as not to fit accurately when engaged without pressure, and to leave space between them for the passage of water to effect the after-fill of the 105 bowl, said valve being forced into accurate water tight engagement with the seat by the pressure of accumulated water in the tank above said valve as the tank fills, and operative 110 connections for said valve.

4. The combination with a flushing tank 115 provided with a flushing outlet and valve seat, of a cup-shaped flushing valve of soft molded rubber, having thin flexible walls decreasing in horizontal diameter toward the lower end of the valve and providing seat engaging portions on the exterior of said walls, said valve having a central vertical aperture therein, a vertical overflow tube extending through and frictionally engaging the central aperture of said valve, said overflow tube being provided with openings above and below the valve and forming the stem of the valve, and operative 120 connections for said valve engaging said overflow tube.

5. The combination with a flushing tank 125 provided with an unobstructed flushing outlet having a valve seat at its upper end, of a hollow valve formed of soft molded rub-

- ber and provided with thin elastic walls, said valve decreasing in horizontal diameter toward its lower end, and providing a seat engaging portion on the exterior of its hollow walls, capable of operatively engaging the valve seat in different angular positions to the vertical of said valve, said valve being provided with a central vertical aperture therethrough, an overflow tube of materially less diameter than the valve seat extending through and frictionally engaging said aperture in the valve, and projecting below said valve, said tube being provided with water apertures above and below the valve, and operative connections for said valve connected with said tube and freely suspending the tube and valve when the valve is unseated, whereby guides for said valve are dispensed with and it will be seated when closed regardless of the perpendicularity of said tube.
6. The combination with a flushing tank provided with an unobstructed flushing outlet having a valve seat at its upper end, of a hollow valve formed of soft molded rubber and provided with thin elastic walls, said valve decreasing in horizontal diameter toward its lower end, and providing a seat engaging portion on the exterior of its hollow walls, capable of operatively engaging the valve seat in different angular positions to the vertical of said valve, said valve being provided with a central vertical aperture therethrough, an overflow tube of materially less diameter than the valve seat extending through and frictionally engaging said aperture in the valve, and projecting below said valve, said tube being provided with water apertures above and below the valve, and operative connections for said valve connected with said tube and freely suspending the tube and valve when the valve is unseated, whereby guides for said valve are dispensed with and it will be seated when closed regardless of the perpendicularity of said tube, and means for arresting the upward movement of said tube and valve before the lower end of said tube is raised above the level of the valve seat, so that pendulous movement of the valve and tube produced by the introduction of water into the tank will not interfere with the seating of the valve when closed.
7. The combination with a flushing tank provided with a flushing outlet and valve seat therefor, of a hollow valve for engaging said seat open at its upper end, and provided with a flexible wall, said valve when in normal position being so constructed that the seat engaging portion of said flexible wall of the valve makes contact at separated portions, only leaving spaces for leakage of water to effect the after-fill of the closet bowl during a portion of the refilling of the tank, the pressure of the water when

the tank is filled distending the flexible wall of the valve to perfectly seat the same, and operative connections for said valve.

8. The combination with a flushing tank provided with a flushing outlet and seat, of a cup-shaped flushing valve formed of soft molded rubber, provided with a flexible wall, a portion of the exterior face of which forms the seat engaging portion of the valve, said valve having a central aperture at its lower end and an interior axial sleeve extending vertically from said aperture, an overflow tube extending through and frictionally engaging said sleeve and aperture, and operative connections for said valve connected with the upper end of said tube.

9. The combination with a flushing tank provided with a flushing outlet and seat, of a cup-shaped flushing valve formed of soft molded rubber, provided with a flexible wall, a portion of the exterior face of which forms the seat engaging portion of the valve, said valve having a central aperture at its lower end and an exterior axial sleeve extending vertically from said aperture, an overflow tube extending through and frictionally engaging said sleeve and aperture, the said seat and the seat engaging portions of said valve being so constructed that they do not fit accurately when engaged without pressure leaving space between them to effect the after-fill of the bowl, the pressure of water in the tank above the valve being effective to distend the walls of said valve into water tight engagement with the seat, and operative connections for the valve connected with said overflow tube.

10. The combination with a flushing tank provided with a flushing outlet and seat, of a cup-shaped flushing valve formed of soft molded rubber, provided with a flexible wall, a portion of the exterior face of which forms the seat engaging portion of the valve, said valve having a central aperture at its lower end and an exterior axial sleeve extending vertically from said aperture, an overflow tube extending through and frictionally engaging said sleeve and aperture, the said seat and seat engaging portions of the valve being constructed so as not to fit accurately when engaged without pressure, and said valve being provided with integral radial webs of rubber extending between the interior sleeve and the flexible wall of the valve, and operative connections for said valve connected with the upper end of the overflow tube, whereby when the valve engages its seat space will be left between them to produce an after-fill of the bowl, and as the tank fills pressure of water above the valve will bring it into water tight engagement with said seat.

11. The combination with a flushing tank provided with a flushing outlet and valve seat, of a cup-shaped flushing valve of soft

5 molded rubber provided with a central aperture therein, a vertically disposed over-
flow tube extending through and friction-
ally engaging said aperture in the valve, said
5 valve having flexible walls, the exterior of
which provide the said engaging portions
of the valve, operative connections for said
valve including depending portions within
10 the tank connected with said tube, and de-
pending portions outside of the tank, the
weight of the valve, its contents of water, the
overflow tube and the depending portions of
said connections within the tank will be
15 substantially counterbalanced by the de-
pending portions of said connections out-
side of the tank when the valve is sub-
merged.

12. The combination with a flushing tank
provided with a flushing aperture and valve
20 seat, of a flushing valve for engaging said
seat, valve operating means including flex-
ible portions, extending from the valve to
the exterior of the tank, a movable cover
25 for the tank provided with supporting
means for engaging the flexible portions
of said valve operating means, said cover
and its supporting portions being so con-
structed that the cover may be removed to-
30 gether with the valve and its operative con-
nections, without disassembling them.

13. The combination with a flushing tank
provided with a flushing aperture and valve
35 seat, of a flushing valve for engaging said
seat, valve operating means includ-
ing flexible portions, extending from the
valve to the exterior of the tank, a movable
cover for the tank provided with support-
40 ing means for engaging the flexible portions
of said valve operating means, said
cover and its supporting portions being so
constructed that the cover may be removed
45 together with the valve and its operative
connections, without disassembling them,
said flexible portions of the valve actuating
means being of such length that by support-
ing the cover vertically on the upper edge
50 of the tank above said valve and seat, the
valve may be operated by said operating
means and its operation observed.

14. The combination with a flush tank

provided with a discharge aperture, and
valve seat, of a hollow flushing valve com-
posed of rubber and having a flexible wall,
the exterior portions of which form the
55 seat engaging portion of the valve, said
seat engaging portions being constructed so
as to normally engage the seat at separated
portions and provided for the leakage of
water past the valve to effect the after-fill
60 of the closet bowl during a portion of the
refilling of the tank, a vertically disposed
overflow pipe extending through said valve
and provided at its lower end with a dis-
charge aperture, and adjacent to its upper
65 end with an overflow aperture, a flexible
connection for operating the valve having
an interior depending portion connected
with said overflow tube, and an exterior de-
pending portion, said tank being provided
70 with means for supporting intermediate
portions of said flexible connection, said ex-
terior portion of the flexible connection and
the interior portion of said flexible connec-
tion, said tube and said valve being in a sub-
75 stantially balanced condition when the
valve and adjacent portion of the overflow
tube are submerged, the pressure of water
within the tank when full distending the
flexible wall of said valve into complete en-
gagement with the valve seat.

15. The combination with a flush tank,
provided with a discharge aperture, and a
valve seat, of a hollow flushing valve for
engaging said seat, said seat and said valve
being, the one formed of flexible material,
85 and the other of substantially rigid ma-
terial, and being constructed to normally
engage each other at separated points, so
as to provide a space between them to effect
the after-fill of the closet bowl through a
90 portion of the refilling of the tank, the pres-
sure of the water upon said valve when
the tank is substantially filled serving to
bring the valve and seat into water tight
95 contact, and operating devices connected
with said valve.

In testimony whereof I affix my signa-
ture.

PHILIP HAAS.
